BRASSIERE VEST

Irwin Greenblatt, Blauvelt, N.Y., and Nicholas A. Marino, Chicago, Ill., assignors to Sears, Roebuck and Co., Chicago, Ill.

Filed Feb. 2, 1973, Ser. No. 329,045

Term of patent 14 years

Int. Cl. D2—01

U.S. Cl. D2—24

Fig. 1.

Fig. 2.

Fig. 3.

Fig. 4.

FIG. 1 is a front elevational view of a brassiere vest showing our new design;

FIG. 2 is a rear elevational view thereof;

FIG. 3 is a front perspective view thereof;

FIG. 4 is a rear perspective view thereof with portions shown broken away.

The characteristic feature of our design resides in two substantially symmetrical panels in a brassiere vest each comprising a cup portion and extending from the shoulder in a tear drop shape, the panels converging between the cups forming the front neckline, all as shown in the drawing.

We claim:

The ornamental design for a brassiere vest, as shown and described.
